UNITED STATES PATENT OFFICE.

CLAES RYDEN, OF CRANSTON, RHODE ISLAND, ASSIGNOR, BY MESNE ASSIGNMENTS,
TO UNIVERSAL WINDING COMPANY, OF BOSTON, MASSACHUSETTS, A CORPORATION
OF MASSACHUSETTS.

STOPPING MECHANISM FOR WINDING-MACHINES.

1,223,620.

Specification of Letters Patent. Patented Apr. 24, 1917.

Application filed November 19, 1914. Serial No. 372,985.

To all whom it may concern:

Be it known that I, CLAES RYDEN, a citizen of the United States, residing at Cranston, in the county of Providence and State 5 of Rhode Island, have invented certain new and useful Improvements in Stopping Mechanism for Winding-Machines, of which the following is a specification.

My invention relates to improvements in 10 winding machines and particularly to the stopping-mechanism therefor. My improved stopping-device is adapted particularly for use on wire-winding machines for winding electrical coils and the object of my invention is to provide means for automatically 15 arresting the winding operation at the completion of each layer of wire so that certain steps in the process of building up the coil can be performed manually.

20 The manner and means for carrying out the invention are fully described in the following specification, illustrated by the accompanying drawings, in which like reference characters designate like parts. In the 25 drawings:—

Figure 1 is a side elevation of a coil-winding machine showing my improved stopping-device applied thereto;

Fig. 2 is an end elevation of the same with 30 certain of the parts removed to more clearly illustrate the traverse-guide mechanism;

Fig. 3 is an enlarged, detail view of a portion 35 of the clutch-controlling and stopping-mechanism, part sectional on the line X—X of Fig. 1, looking in the direction indicated by the arrow x;

Fig. 4 is an enlarged, sectional view taken 40 on the line Z—Z of Fig. 2, looking in the direction indicated by the arrow z, and illustrating the relation between the stopping-device and the traversing-mechanism; and

Fig. 5 is a sectional plan view taken on the line V—V of Fig. 4, looking in the direction indicated by the arrow v.

45 My invention is herein shown and described as applied to a machine of the type illustrated and described in an application for patent, Serial No. 748,221, filed Feb. 13, 1913, by Max Helm. In general, this type 50 of machine embodies an arrangement of two or more traverse-guides adapted to be simultaneously reciprocated longitudinally of a rotating winding-spindle or mandrel on which the coil is wound. One of the guides 55 is traversed at a relatively slow rate of

speed to lay the wire in close spirals or turns arranged side by side the length of the coil; while another guide is reciprocated with a much faster traverse to wind on insulating-material, such as yarn or thread, diagonally 60 or cross-wise of the wire windings. The strands of insulating-material being crossed many times over and under the wire-windings of each layer of the coil are woven in and out among the turns of the wire and 65 thus form a mechanical binder or reinforcement for the coil to link the wire-windings together and hold them in place. While my present improvement is particularly adapted for this style of winding machine, and 70 while I have preferred to describe and illustrate it in connection therewith, it is also to be understood that the invention is applicable to other arrangements of winding mechanism and could be employed thereon 75 to function for the same purpose without material change in its construction.

Referring to Figs. 1 and 2 of the drawings, A designates the main frame of the machine which is constructed with bearings 80 for the rotating winding-spindle or coil-mandrel b. The spindle b is driven through the medium of a driving-pulley B with which it is connected by suitable clutch-devices, shown at B' but not here illustrated in 85 detail. The frame A also carries bearings for a cam-shaft c arranged below and parallel with the spindle b, and adapted to be driven therefrom by suitable connections such as the pulleys B², B³, connected by a belt 90 b', and a train of gearing located within the case or housing A'. These connections being well known and long used in the winding art are not herein shown or described in detail.

95 The cam-shaft c carries two or more cams for reciprocating the several traverse-guides of the machine, only two, C and C' being employed in the present construction. The cam C is mounted fast on the shaft c and is driven directly therefrom through any suitable arrangement of key or spline, not here shown. The cam C' is, however, mounted free rotatively of the shaft c and is driven from independent means so that it may be 100 rotated at a much slower rate of speed than that of the cam C. Any suitable means may be employed for driving the cam C' from the winding-spindle b independently of the cam C, such, for instance, as that 105 110

shown in the application for patent previously referred to, or through the medium of a worm-gear c' secured to its hub. The driving connections between the worm-gear c' and spindle b are not here shown in detail, but are preferably of the type illustrated in my pending application for patent, Serial No. 843,794, filed June 8, 1914.

The winding-spindle b projects outwardly beyond the front of the frame A and is adapted to receive the windings as they build up in the form of the cylindrical coil W , illustrated by dot-and-dash lines in Figs. 1 and 2. The guides for the wire and insulating-material are arranged to be reciprocated on opposite sides of the spindle b as shown in Fig. 2, and are designated respectively G and G' . The guide G' for the insulating-material, called for convenience the thread-guide, has no particular function in connection with the stopping-mechanism which forms the subject-matter of the present application, and therefore it will not be described in detail. Suffice to state that it consists essentially of a pivoted arm g adapted to slide on a horizontal rod h arranged parallel with the winding-spindle b , and carries a downwardly-extending arm g' which slides in a groove on the parallel rod h' . The arm g' is connected by a suitable link to a rockable lever, not here shown, but arranged to be oscillated from the cam C , as shown and described in my U. S. Letters Patent No. 1,141,583, granted June 1, 1915. The guide proper comprises a forked extension of the arm g formed with two branches g^2, g^3 having slots through which the yarn y leads. The lower fork g^2 is bent back at its end to provide a bearing face which rests against the surface on which the winding is being performed. As the winding increases in diameter the guide G' swings upwardly on the pivot formed by the rod h .

The wire-guide G has substantially the same arrangement of supporting rods as the thread-guide G' but differs slightly therefrom in structural details. As shown in Figs. 1 and 2, two parallel, horizontal rods e, e' are supported at one end in a bracket E fastened to the side of the main frame A of the machine and project outwardly therefrom beyond the end of the winding-spindle b . The outer ends of the rods e, e' are tied together by an arm or bracket E' which, for the sake of clearness, is not shown in Fig. 2. Surrounding the rod e and adapted to slide thereon is a sleeve d , and the rod e' also carries a similar sliding sleeve d' . The sleeves d and d' are connected by a vertical arm D formed with a central, longitudinal slot d^2 . The upper end of the arm D is fixedly secured to the sleeve d by means of the ears d^3, d^3 which are bent around its circumference and clamped thereto by the screws d^4 ,

d^4 . The lower end of the arm D is formed to partly encircle the sleeve d' between the two shoulders or flanges d^5, d^5 , leaving the sleeve free to turn on the rod e' , but holding it longitudinally in relation to the arm D . In this way the sleeve d' is allowed to turn on its axis while being caused to slide on the rod e' under action of the arm D . Referring particularly to Fig. 2, the sleeve d' is formed with two lugs or ears d^6, d^6 , see also Fig. 1, to which is attached the lower end of the wire-guide arm g^4 . The upper end of the arm g^4 carries a yoke g^5 provided with bearings for a rotatable guide-wheel g^6 formed with a circumferential groove g^7 through which the wire w leads. An auxiliary, grooved wheel or pulley g^8 is mounted rotatively on an upwardly-extending arm g^9 of the yoke g^5 , see Fig. 1, and the wire w leads partly around and under this pulley to direct it to the groove in the wheel g^6 as shown more clearly in Fig. 2. As the wire is built up in layers on the coil W the guide-wheel g^6 is free to move back from the axis of the winding-spindle through the pivotal action of the arm g^4 on the rod e' .

The arm D which acts to traverse the guide G back and forth along the winding-spindle is reciprocated from an oscillating lever F pivoted at f on an extension E^2 of the bracket E , see Fig. 1. The lever F is oscillated through the engagement of a stud or roll f' on its lower arm f^2 with the groove e^2 of the cam C , see also Fig. 3. The means for connecting the two arms D and F consists of a rod or link K having suitable devices k, k' at its ends for engaging the slot d^2 of the arm D and a similar slot f^3 in the arm F . Preferably the engaging-means k and k' are adjustable longitudinally of the slots d^2 and f^3 to provide for altering the extent of traverse imparted by the lever F to the guide G , so that the length of the layers of winding can be regulated at will without changing the cam C or its connections. It will be noted, therefore, that the length of traverse of the guide G can be altered to provide for winding coils of different lengths without changing the throw of the cam C or the range of oscillation of the lever F . This latter point is of importance since the lever F acts as a means for stopping the machine at the end of each traverse of the guide as will be explained more fully hereinafter.

Referring now to Figs. 1, 2 and 3, the manual starting and stopping of the machine is controlled by means of a handle or lever L secured to the end of a rock-shaft l which is mounted in bearings a, a at the top of the frame A . At its rearward end the rock-shaft l carries an arm or lever L' , not shown in Fig. 2, adapted to operate the clutch-mechanism which connects the driving-pulley B rotatively with the spindle b . The ar-

angement of these parts may be in accordance with the usual practice, as well known in the winding art, and therefore this portion of the mechanism will not be described in detail. In United States Patent No. 834,779, granted to S. W. Wardwell Oct. 30, 1906, there is shown a clutch-device particularly adapted to machines of the present type and such a form of mechanism is preferably here employed. To release the clutch from the driving pulley B the lever L' is rocked in the direction indicated by the arrow u, Fig. 3, by means of a spring l². It is also to be noted that the lever L' carries a brake-shoe m which is engaged with the periphery of a flanged disk M rotating with the winding-spindle after the disengagement of the clutch-devices. This arrangement is also common to machines of the present type and is provided to effect a prompt arrest of the rotation of the spindle against its tendency to continue to rotate from momentum. Normally, during the operation of the machine, the lever L' is maintained in the position illustrated in Fig. 3, with the brake-shoe m free from the brake-disk M, through the means of suitable detent-devices now described: It has been stated that the lever L' is fast on the rock-shaft l, and the hand-lever L is also secured fast thereto by means of the screw l³ so that these parts all move together. Referring to Fig. 3, the lever L is formed with a downwardly curved arm or extension l² carrying a projecting lug or detent-shoulder l⁴. The shoulder l⁴ is adapted to be engaged by a corresponding detent-shoulder n formed on a pivotally-mounted lever N. As here shown the lever N is pivoted on a stud n' screwed into the front of the frame A of the machine and is formed with a finger-extension n². By pressing down on the finger-piece n² the opposite end of the lever N can be raised to disengage the detents l⁴ and n, thereby releasing the lever L to allow the operation of the clutch-lever L' under action of its spring l². The detents l⁴ and n are engaged by rocking the lever L' in the direction opposite to that indicated by the arrow u in Fig. 3, and are maintained in engagement through the action of gravity or by means of a spring n³ operating on the lever N. As shown in Fig. 3, the spring n³ is preferably made in the form of a ring encircling the hub of the lever N and having one of its ends hooked over the edge of the main frame A, while its opposite end is bent laterally and hooked into a hole in the arm n² of the lever N. While the detents are in engagement the clutch-lever L' is held released from the clutch-devices to allow the latter to engage the driving-pulley B to cause the rotation of the winding-spindle b and the operation of the other parts of the machine. The means for arresting the operation of the machine automatically are ar-

ranged to act to lift the lever N to free the detents in the manner and for the purpose as next described:

It will be noted from Fig. 3 that the lever N is extended forwardly beyond its detent-shoulder n and formed with a downwardly projecting arm n⁴. Adjustable up and down on the end of the arm n⁴ is a slidable member n⁵ held in place by a screw n⁶ reaching through a slot n⁷ and screwed into the arm, 70 see also Fig. 4. The member n⁵ has a right-angled extension n⁸ at its end adapted to be engaged by the end of a slidable rod O which forms an essential part of the automatic stopping-device of the machine. The 80 rod O slides in a bearing o fastened to the side of the upright arm e² of the bracket E. The lower end of the rod O is beveled off at o' and reaches through a hole p in the wall of a tubular bearing-member P. The member P forms a part of or is attached to the arm E² which extends from the bracket E. As shown in section in Fig. 4, the member P comprises two opposite, tubular portions p' and p² bored to serve as bearings for the 85 opposite ends of a rod R. Screwed into the ends of the bores of the bearings p' and p² are plugs p³ and p⁴ having reduced portions p⁵ and p⁶ against which bear the coiled springs s, s. The opposite ends of the 90 springs s bear on the ends of the rod R. Two check-nuts p⁷, p⁸ on the ends of the plugs p³ and p⁴ bear against the ends of the member P to lock the plugs from turning, and by loosening the nuts the plugs can be 95 adjusted to vary the tension of the springs s. In this way the pressure on each end of the rod can be altered to adjust the rod R longitudinally of its bearings to bring it 100 into its proper operative position as later described. At its right-hand end, as viewed in Fig. 4, the rod R is formed with a V-shaped notch r in which the beveled end of the rod O seats. A coiled spring o² bearing against a collar o³ on the rod O with its opposite end held against the bearing o acts to force the rod downwardly to maintain its end seated in the notch r of the rod R. Referring to Figs. 4 and 5, the rod R is cut away at r' midway of its ends to form two 105 shoulders r² and r³. The lower end of the arm f² of the lever F is arranged to play back and forth along the reduced portion r' of the rod R with its sides adapted to strike against the shoulders r² and r³ at each 110 extreme of its oscillation to slide the rod longitudinally against the action of its springs s, s. The operation of the complete machine is as follows:

Before starting the machine to wind a 115 coil the operator first adjusts the wire-guide G to one extreme of its traverse along the spindle b. The wire w is now drawn down from its source of supply, usually placed above the machine, but not here shown, led 120 above the machine, but not here shown, led 125

over the guide-wheels g^8 and g^6 and its end is then fastened to the spindle b or to the arbor on which the coil is to be wound. The thread or yarn y is drawn up from its supply spool or cop, not here shown, passed through the guide notches at the ends of the arms g^3 , g^2 on the guide G' and its end also secured to the spindle b . To start the machine the operator rocks the handle L in the direction indicated by the arrow t , Fig. 2, and the clutch-devices are thereby released to connect the driving-pulley B with the spindle b as previously explained. The rocking of the lever L causes the detents n and l^4 to be engaged to maintain the driving-connections of the machine operative and the two cams C and C' will be driven from the spindle b through the connections previously explained. The rotation of the cam C' causes the lever F to be rocked to reciprocate the guide G with a relatively slow movement, while the cam C imparts a very much faster traverse to the thread-guide G' through the medium of connections similar to those of the guide G . The guide G as it moves slowly from one extreme of traverse to the other, during the rotation of the winding-spindle, lays the wire w in closely-adjacent helices to form one layer of the coil W . Meanwhile, the thread-guide G' is being reciprocated with a much faster traverse to cross the yarn y back and forth, over and under the wire coils in openly-spaced helices which form the binding and reinforcing medium previously referred to. With this system of winding it is the usual practice to employ an insulated wire in the manufacture of the coils, and in most cases it is not required to introduce an insulating-medium between the different layers of the coil. As a matter of fact, the yarn-windings serve in a measure for insulation between the wire layers and although generally the layers will not be entirely covered with yarn at their completion, still enough yarn will have been wound on to coöperate with the primary insulation of the wire so that the insulation of the wire throughout the coil is augmented and made more efficient. This method of inserting yarn windings between the layers of wire in the coil is fully described in United States Letters Patent No. 1,080,830, granted December 9, 1913, to Max Helm.

In some instances, however, where the coils are intended for high-tension current, it has been found of advantage to introduce an added insulating medium between the layers of the coil to guard against short-circuiting or leakage. The simplest and most economical method of applying this added insulation is to insert strips of paper or other suitable material between the layers of the coil. This step in the process of manufacturing the coil is usually performed

manually and for this reason the winding operation must be stopped at the end of each traverse of the wire-guide G . To accomplish this automatic stopping of the machine for the purpose mentioned I have devised the means which form the essence of the present invention, and the method of their operation is as follows: It has been explained that the lower arm f^2 of the lever F which reciprocates the wire-guide G travels back and forth between the shoulders r^2 and r^3 of the rod R . The distance between these shoulders is slightly less than the distance between the extremes of movement of the sides of the arm f^2 , and hence the shoulders are adapted to be engaged by the arm to move the rod R in one direction or the other according to the direction of movement of the lever F . That is to say, each time the lever F approaches either extreme of its throw, in bringing the wire-guide G to the end of its traverse, the arm f^2 will engage the appropriate shoulder r^2 or r^3 on the rod R to slide the latter longitudinally in its bearings against the action of the springs s . This longitudinal movement of the rod R , in either direction, will cause the end of the vertical rod O to ride up on the beveled sides of the notch r against the action of its spring o^2 . As the rod O is projected upwardly its upper end will be brought into contact with the member n^5 on the lever N to raise the latter and release the detents n and l^4 . This action frees the hand-lever L and causes the operation of the clutch-disengaging means and braking-mechanism as previously described. In this manner the operation of the machine is automatically arrested at the instant the wire-guide completes each layer of winding. The adjustment of the member n^5 on the lever N provides for a more accurate setting of the stopping-device to act at the proper instant and by adjusting the tension of the springs s , as before described, the rod R can also be set in proper relation to the throw of the arm f^2 .

After the machine has been stopped at the completion of the layer of wire-windings, the operator fastens the strip of paper or other insulation around the outside of the coil and then repeats the operation of starting the winding again. In starting up the machine the hand is held on the lever L an instant until the arm f^2 has moved back from the shoulder on the rod R and in the meantime the rod will be returned to its normal position under action of the springs s so that the rod O will again seat itself in the bottom of the notch r with its opposite end removed from contact with the arm N . The detents on the levers L and N will then become engaged to maintain the machine operative as before described.

It has been previously stated that with

this method of building up the coil the 5
yarn-windings do not cover the whole
length of each layer of wire-windings, but,
on the contrary, a portion of the layer is
left with relatively few turns of yarn show-
ing on its surface. Usually, however, two-
thirds or three-fourths of the length of the
wire layer is covered and protected by the
yarn-windings and hence only a relatively

10 narrow strip of paper insulation is required.
That is to say, whereas with the usual sys-
tem of producing insulated coils it is neces-
sary to insert sheets of the insulating-
material of a width equal to the length of
15 the coil, in the present instance relatively
narrow ribbons take the place of these wide
sheets and it has been found that they can
be applied with much greater facility and
convenience.

20 Various modifications might be made in
the form and construction of the parts of
my new device without departing from the
spirit or scope of the invention; therefore,
without limiting myself to the exact em-
25 bodiment shown and described, what I
claim is:—

1. In a winding machine, the combina-
tion with the rotating winding-spindle and
reciprocating traverse-guide, of means for
30 rotating the spindle, an oscillating rocker-
arm for reciprocating the guide, stopping-
mechanism for arresting the operation of
the spindle and guide, and means engaged
35 by and actuated from the rocker-arm to
cause the action of the stopping-mechanism
when the guide reaches either extreme of
its throw.

2. In a winding machine, the combina-
tion with a winding-spindle, of means to
40 rotate said spindle, a plurality of traverse-
guides adapted to be traversed longitudi-
nally of the spindle, means for reciprocating
the guides at different speeds, and
means for automatically arresting the op-
45 eration of the spindle and guides when one
of the latter reaches its extreme of traverse
in either direction.

3. In a winding machine, the combina-
tion with a rotating winding-spindle, of a
50 traverse-guide adapted to be reciprocated
with respect to the spindle, an oscillating
arm for reciprocating the guide, stopping-
mechanism for arresting the operation of
the spindle and guide, a sliding-member
55 engaged by and operated from the move-
ment of the guide-reciprocating arm at each
extreme of its throw, and means actuated
by the sliding-member to operate the stop-
ping-mechanism when the guide reaches
60 the end of its traverse.

4. In a winding machine, the combina-
tion with a rotating winding-spindle, of
means to rotate the spindle, a plurality of
traverse-guides adapted to be traversed lon-
65 gitudinally of the spindle, means for re-

ciprocating the guides at different rates of
speed, stopping-mechanism for arresting
the operation of the spindle and guides, and
means adapted to actuate the stopping-
mechanism at certain intervals of the wind- 70
ing, said means actuated from the recipro-
cating-means of one of the guides but inde-
pendently of the reciprocation of the other
guide.

5. In a coil-winding machine, the combi- 75
nation with a winding-spindle, of means to
rotate said spindle, a wire-guide adapted
to be traversed longitudinally of the spin-
dle, a guide for insulating-material also
adapted to be traversed along the spindle, 80
means for reciprocating the guides at dif-
ferent rates of speed with the insulating-
material-guide having several traverses to
one traverse of the wire-guide, and means
to arrest the operation of the winding 85
spindle and both guides when the wire-
guide reaches either end of its traverse
without respect to the position of the other
guide.

6. In a coil-winding machine, the combi- 90
nation with a winding-spindle, of means to
rotate said spindle, a wire-guide adapted
to be traversed longitudinally of the spin-
dle, a guide for insulating-material also
adapted to be traversed along the spindle, 95
means for reciprocating said guides with
the insulating-material-guide having sev-
eral traverses to one traverse of the wire-
guide, stopping-mechanism adapted to ar-
rest the operation of the winding-spindle 100
and both guides, and means uninfluenced by
the insulating-material-guide but controlled
by the position of the wire-guide to actuate
the stopping-mechanism at each end of the
wire traverse. 105

7. In a coil-winding machine, the com-
bination with a winding-spindle, of a wire-
guide adapted to be reciprocated longitudi-
nally of the spindle, a guide for insulating-
material also adapted to be reciprocated 110
along the spindle, means for rotating the
spindle, separate means for reciprocating
the different guides, stopping-mechanism
for arresting the operation of the spindle
and guide, a member adapted to be moved 115
from one of the guide-reciprocating-means
at each end of the traverse of the wire-guide,
and means operated from said member to
actuate the stopping-mechanism when the
wire-guide reaches either extreme of trav- 120
erse.

8. In a winding machine, the combination
with a rotating winding-spindle, of a re-
ciprocating traverse-guide, means to rotate
the spindle, an oscillating rocker-arm for 125
reciprocating the guide, stopping-mecha-
nism for arresting the operation of the
spindle and guide, detent-means for main-
taining said stopping-mechanism normally
inoperative, and means engaged by and ac- 130

tuated from the rocker-arm to release the detent-means to cause action of the stopping-mechanism when the traverse-guide reaches the end of its traverse.

5 9. In a winding machine, the combination with a rotating winding-spindle, of means to rotate the spindle, a reciprocating traverse-guide, an oscillating rocker-arm for reciprocating said guide, stopping-mechanism to arrest the operation of the spindle and guide, detent-means for maintaining said stopping-mechanism normally inoperative, a slideable member engaged by and operated from the rocker-arm at the end of each traverse of the guide, and means engaging the sliding member and moved therefrom to release the detent-means to cause action of the stopping-mechanism.

10 10. In a winding machine, the combination with a rotating winding-spindle, of means to rotate said spindle, a reciprocating traverse-guide, an oscillating arm for reciprocating said guide, a slideable rod having abutments adapted to be engaged by said arm at its extremes of throw, a second rod engaging the first rod to be moved thereby through the movement of the first rod in either direction, and means actuated from the movement of the second rod to arrest the operation of the machine.

15 11. In a winding machine, the combination with a rotating winding-spindle, of a reciprocating traverse-guide, means to rotate the spindle and reciprocate the guide, stopping-mechanism to arrest the operation of the spindle and guide, a sliding member adapted to be moved in either direction by the guide-reciprocating-means, tension-means acting on the member to maintain it in a mean position relative to the reciprocating-means, and means engaging the sliding member to be operated from its movement in either direction to actuate the stopping-mechanism when said member is moved out of its mean position.

20 12. In a winding machine, the combination with a rotating winding-spindle and reciprocating traverse-guide, of means to rotate the spindle and reciprocate the guide, stopping-mechanism to arrest the operation of the spindle and guide, a member adapted to be moved in opposite directions from the guide-reciprocating-means, a second member engaging said movable member to be operated thereby to cause action of the stopping-mechanism, and resilient means acting on said movable member to normally maintain it in a mean position in relation to the reciprocating-means while allowing it to be moved thereby in either direction.

25 13. In a winding machine, the combination with a winding-spindle and traverse-

guide, of means to rotate the spindle and reciprocate the guide, stopping-mechanism for arresting the operation of the spindle and guide, a rod slideable in either direction and adapted to be operated from the guide-reciprocating-means, a member engaging said rod and operated from its sliding movement in either direction to cause action of the stopping-mechanism, springs engaging the ends of the rod to normally maintain it in a mean position in relation to the reciprocating-means, and means to adjust the tension of the springs. 75

14. In a winding machine, the combination with a winding-spindle and traverse-guide, of means to rotate the spindle and reciprocate the guide, stopping-mechanism for arresting the operation of the spindle and guide, a rod adapted to be engaged by the reciprocating-means to slide it in either direction, tubular bearings for slidably supporting said rod, springs in said bearings engaging the ends of the rod, studs screwed into said bearings to hold the springs under tension, and means operated from the movement of the rod under action of the reciprocating-means to cause the operation of the stopping-mechanism. 90

15. In a winding machine, the combination with a winding-spindle and traverse-guide, of means to rotate the spindle and reciprocate the guide, stopping-mechanism to arrest the operation of the spindle and guide, detent-means for maintaining said stopping-mechanism normally inoperative, a slideable rod adapted to be moved from the guide-reciprocating-means at either end of the traverse of the guide, said rod formed with beveled shoulders, and a second rod engaging the shoulders on the first rod to be moved thereby to release the detent-means. 100

16. In a winding machine, the combination with a rotating winding-spindle and a reciprocating traverse-guide, of means to rotate the spindle, an oscillating rocker-arm for reciprocating the guide, stopping-mechanism for the spindle and guide, a detent to prevent the operation of the stopping-mechanism, and a member mounted parallel to the spindle and operatively associated with the detent, said member adapted to be engaged by and moved from the rocker-arm at the end of each traverse of the guide to trip the detent and release the stopping-mechanism. 105

In testimony whereof I affix my signature in presence of two witnesses.

CLAES RYDEN.
